UNITED STATES PATENT OFFICE.

WILLIAM C. SMITH, OF CLEVELAND, OHIO, ASSIGNOR, BY MESNE ASSIGNMENTS, TO
A. E. MERKEL, OF CLEVELAND, OHIO.

WIRE-FENCE MACHINE.

1,174,771.

Specification of Letters Patent.

Patented Mar. 7, 1916.

Application filed February 14, 1912, Serial No. 677,630. Renewed July 31, 1915. Serial No. 43,029.

To all whom it may concern:

Be it known that I, WILLIAM C. SMITH, a citizen of the United States, resident of Cleveland, county of Cuyahoga, and State of Ohio, have invented a new and useful Improvement in Wire-Fence Machines, of which the following is a specification, the principle of the invention being herein explained and the best mode in which I have contemplated applying that principle, so as to distinguish it from other inventions.

My invention relates to wire-fence machines, and particularly to that class of wire-fence machines in which the line-wires and stay-wires are fed into the machine automatically and the completed fence is discharged automatically therefrom.

The object of my said invention is to combine in one machine coöordinated elements which will automatically perform the functions of the two separate machines shown, described and claimed in U. S. Patents Nos. 689,430 and 689,488, issued December 24, 1901, on inventions made jointly by me and Jonathan Harris; and thereby increase the speed of the operation of and coincidentally decrease the cost of manufacturing the fence which said previously patented machines were designed by their joint use to manufacture.

More specifically my said object is to combine in a single automatically operating machine, mechanism which will form stays provided at intervals therealong with crimped loops, feed line-wires, carry such crimped loops into the vicinity of such line wires, and effect the engagement of such loops and line wires to form the lock shown, described and claimed in U. S. Patent No. 689,465 issued December 20, 1901, to Simeon C. Davis.

To this end my said invention consists of means hereinafter fully described and particularly set forth in the claims.

The annexed drawings and the following description set forth in detail certain means embodying my invention, the disclosed means, however, constituting but one of various mechanical forms in which the principles of my invention may be applied.

In said annexed drawings: Figure 1 represents a front elevation of a wire-fence machine embodying my invention. Fig. 2 represents a rear-elevation of said machine.

Fig. 3 represents a side-elevation of such machine as viewed from the right hand. Fig. 4 represents a side elevation thereof as viewed from the left hand. Fig. 5 represents a top-plan with the central transverse portion of the machine broken away. Fig. 6 represents a vertical longitudinal section of the entire machine taken upon the planes indicated by line VI—VI in Figs. 3 and 7 and viewed in the direction indicated by the arrows. Fig. 7 represents a vertical transverse section taken upon the plane indicated by the line VII—VII in Fig. 5 and viewed in the direction indicated by the arrows. Fig. 8 represents a perspective view of a fragmentary part of the machine upon an enlarged scale, including the stay-wire feeding-means, the means for intermediately supporting the stays, and adjacent elements or parts thereof. Fig. 8^a represents the knife used in severing the stay-wire to form separate stays. Fig. 9 represents a perspective view, also upon an enlarged scale, of a fragmentary part of the machine including the means for guiding one of the line-wires into the machine. Fig. 10 represents a rear elevation of the parts shown in Fig. 8, and upon the same scale. Fig. 11 represents a cross-section of parts shown in Fig. 10, taken upon a plane indicated by line XI—XI in said Fig. 10, and viewed in the direction indicated by the arrows. Fig. 12 represents upon an enlarged scale, a vertical transverse section of a fragmentary part of the upper portion of the machine, and taken upon the same plane as is that section illustrated by Fig. 7. Fig. 12^a represents a side elevation of parts shown in Fig. 12, together with fragmentary parts of connected elements. Fig. 12^b on the last sheet, represents a perspective view of still other parts shown in said Fig. 12, and particularly one of the fingers used for carrying the stays from the loop-crimping means to and partially through the stay-guiding channels. Fig. 13 represents in perspective and upon an enlarged scale one of the multiplicity of bending, twisting and loop-crimping means, with fragmentary portions of connected parts. Fig. 14 represents a vertical transverse section of one of the multiplicity of die-members included in the parts illustrated by Fig. 13. Fig. 14^a represents a longitudinal vertical section of the

parts shown in Fig. 14 and taken upon the planes indicated by line XIV^a—XIV^a in Fig. 14. Figs. 15, 16 and 17 each illustrate in perspective, an axial section of a fragmentary portion of one of the multiplicity of the twisting-bars, a fragmentary portion of a stay, and one of the multiplicity of bending plungers, depicting their several relations in successively occurring positions.

10 Fig. 18 represents, in perspective, a vertical section of one of the multiplicity of movable crimping dies, and one of the multiplicity of the complementary crimping punches, together with a fragment of the frame in which the latter is mounted, and a fragmentary part of a stay with a completed loop formed therein in place on one of said dies. Fig. 19 represents a horizontal section of a fragmentary portion of the machine taken upon the plane indicated by line XIX—XIX, in Fig. 7, and viewed in the direction indicated by the arrows. Fig. 20 represents a top plan, on an enlarged scale, of a fragmentary portion of the machine, showing parts in horizontal section, and including part of the driving mechanism. Fig. 21 represents a vertical section of the parts shown in Fig. 20, taken upon the plane indicated by line XXI—XXI in said figure, and viewed in the direction indicated by the arrows. Fig. 22 represents a vertical section of parts also shown in Fig. 20 taken upon the plane indicated by line XXII—XXII in said figure and viewed in the direction indicated by the arrows. Fig. 23 represents a horizontal section of a fragmentary part of the machine and showing part of the stay-guiding means and stay-carrying means in top plan. Fig. 24 represents a vertical section of the parts shown in Fig. 23 and taken upon the plane indicated by line XXIV—XXIV in said figure. Fig. 25 represents, upon an enlarged scale, a side elevation of one of the multiplicity of dies and connected parts used in connection with the operation of effecting the engagement of the loops of the stays with the line-wires together with a fragmentary portion of one of the keepers coöperating therewith. Fig. 25^a represents in perspective, one of the multiplicity of pairs of clamping-jaws, detached, and coöperating with said dies and keepers to effect the said engagement. Fig. 26 represents a front elevation of three of such dies and connected parts, together with fragmentary portions of the corresponding keepers. Fig. 27 represents a bottom plan of the single die shown in Fig. 25, showing also the corresponding keeper in horizontal section therein. Fig. 28 represents a vertical section of one of the dies, taken upon the plane indicated by line XXVIII—XXVIII in Fig. 26, and viewed in the direction indicated by the arrows. Fig. 29 represents a vertical section of the said die

taken upon the plane indicated by line XXIX—XXIX in Fig. 28. Fig. 30 represents a vertical transverse section of a fragmentary portion of the machine taken upon the plane indicated by the line XXX—XXX in Fig. 1, and viewed in the direction indicated by the arrows. Fig. 31 represents in elevation a detail portion of the machine and including a portion of that part of the mechanism designed to twist the ends of the stays around the outermost or finishing line wires of the fence. Fig. 32 represents, upon an enlarged scale, a section of the parts shown in Fig. 31, taken upon the plane indicated by the line XXXII—XXXII in said figure. Fig. 32^a represents a front elevation of the keeper and holder operating in connection with the winding devices the view being taken upon the plane indicated by line XXXII^a—XXXII^a of Fig. 32. Fig. 33 represents a plan of the parts shown in Fig. 31. Fig. 34 represents a fragment of one of the outermost line-wires and of a stay, showing the end of the latter wound around the former.

90 The illustrated embodiment of my invention comprises the following coöordinated main elements all combined in a unitary and automatically-operating structure, namely: means for feeding a stay-wire in the direction of its axis; means for severing the said wire to form stays; means for simultaneously forming a multiplicity of bends in such stay; means for simultaneously twisting the bends to form loops; means for crimping such loops; means for effecting the engagement of said loops and a corresponding number of line-wires to form locks; means for simultaneously feeding such line-wires through the sphere of operation of said lock-forming means; means for carrying the stays to the bending-means; means for carrying the stays to the crimping-means; and means for carrying the stays to the lock-forming means, said carrying means including a guide and means for moving the stay therethrough. A main-frame A is provided for supporting all of the above-named main-elements together with all of the driving-mechanism and the parts for effecting the coöordination of said main-elements. The driving mechanism includes a horizontal main driving shaft B mounted in the lower part of the frame and having keyed upon its left-hand end, a large gear B' meshing with a pinion B², Fig. 4, secured to a stub-axle B³ to which is also secured a gear B⁴. This latter gear meshes with a pinion B⁵, secured to a second stub-axle B⁶ on which is fixed the driving-pulley B⁷, suitable bearings secured to the adjacent part of frame A being provided for these axles, as will be readily understood. This large gear B' drives a train of gears b and b', and the latter drives an upper secondary driving-

95 10 11 12 13

shaft B^8 , Fig. 5. At the right-hand end of secondary-shaft B^8 is secured a bevel-pinion b^2 which drives a bevel-gear b^3 secured to an upper transverse shaft B^9 on which are secured a number of cams and other elements whose location and functions will be herein-after further described. The right-hand end of the main-shaft extends beyond the frame A, drives the reels and performs other functions also hereinafter further described.

Stay-wire feeding means.—Fixed upon the transverse shaft B^9 is a cam C, Fig. 3, which engages a roller c , fixed to a yoke C' which straddles shaft B^9 , as shown in Fig. 6, and carries at its upper end a vertically extending rack C^2 which meshes with a pinion c^7 loosely mounted upon a counter-shaft C^3 , Figs. 5 and 20. This pinion has an extension formed with ratchet teeth c' located within a recessed gear C^4 , Figs. 21 and 22, and said teeth are engaged by a series of spring-pressed pawls c^2 fixed to said recessed gear. These teeth and pawls are so arranged that when the rack C^2 moves upwardly, rotation of gear C^4 will be effected, and upon the downward rack-movement, it remains stationary. Intermittent rotation of gear C^4 is therefore, it will be noted, effected. This gear C^4 meshes with a pinion c^3 fixed to a second countershaft c^8 , Figs. 8, 19 and 20, which also carries a gear c^4 fixed thereto meshing with a pinion c^5 fixed to countershaft C^3 . The rear end of said shaft C^3 has fixed upon it, a grooved and toothed feed-roll C^5 , Figs. 8 and 10. The teeth of this roll mesh with the teeth of a second grooved feed-roll C^6 mounted upon a rod c^6 mounted so as to be adjustable toward and from the counter-shaft C^3 , in any suitable well-known manner, whereby the distance between the contiguous portions of the peripheries of the two feed-rolls may be varied, so that the feeding-pressure exerted upon the wire fed by such rolls may be adjusted to assume the proper degree, as will be readily understood. Fixed to the frame A, adjacent to the feed-rolls C^5 and C^6 , is an extension A', provided with guide-rollers, as shown, for leading the stay-wire S through an aperture a and between the feed-rolls. Alined with the said feed-rolls is a guiding tube a^8 passing through a housing a' secured to the frame A, Figs. 5, 8 and 10.

Means for forming the bends.—Formed in the upper surface of the frame A, is a dove-tail groove a^2 , Figs. 5, 7 and 12, extending parallel with the direction of stay-wire feed. In this groove are seated a plurality of alined bending devices E, corresponding in number with the number of intermediate line-wires which form a part of the fence which the machine is designed to construct. In the illustrated embodiment of my invention these line-wires are nine in number. Each of these bending devices,

excepting the middle one which is fixed, comprises in its structure a housing E', Figs. 12, 13, 14 and 14^a, formed with a tongue e engaging the groove a^2 and having secured thereto a fixed bolt e' extending through slots a^3 , and passing through the frame. The lower end of each of these bolts extends through a slot f formed in the end of a lever F, pivoted upon the lower side of the adjacent portion of the frame A, as shown in Fig. 19. Four of these levers, those on one side of the central or fixed bending device, articulate at one end with a transverse bar F' , and the corresponding ends of the other four levers, articulate with a bar F^2 , see also Fig. 5. The outermost of the second-named four levers articulates with a bar F^3 , at a point intermediate of the lever's pivotal point and the point of its articulation with the corresponding bolt e' , which in turn articulates with the bar F' . The pivotal axes of these two sets of levers vary in distance from the axes of their corresponding bolts e' . The outermost of each of these sets of levers is pivoted farthest from its bolt-axis, and this pivotal distance decreases with each successive lever of each set, as shown. It will therefore be noted

that a reciprocating movement upon the part of bar F' will effect the oscillation of levers F upon their pivotal axes. The variation of the location of the pivotal axes, however, will cause those arms of the levers which articulate with the bending devices to oscillate through arcs of various lengths and hence effect reciprocating movements upon the part of the housings E' of various amplitudes. The reciprocating movement of the bar F' , therefore, in the direction of the arrow in Fig. 19, will cause each member of each of the two groups of housings to move inwardly toward the middle or fixed bending device, by virtue of the arrangement and connection of bars F' , F^2 and F^3 . In addition to this movement, however, each housing will furthermore have a movement relatively to its adjacent housing, so that during the described movement of bar F' , the distance between the successive movable housings will be lessened. The lengths of the levers and positions of their pivotal axes are made such that this described lessening of distances will equal exactly the lessening in distances between each other on the part

of points in a stay-wire which are located in the wire and upon the center of the bends, and which takes place when a straight wire is formed with a plurality of bends which lessens the distance between its extremities. When the bar F' is moved in the opposite direction, it will of course follow that the housings will move outwardly from the center or fixed housing and increase their respective distances from each

other. Each such housing is formed with a vertically extending groove e^2 , Figs. 12 and 13, in which slides a die-member E^2 , which consists of a main-portion e^3 formed 5 with a recess e^5 opposite a bore e^4 formed in the housing, a die e^6 and two oscillatory stay-seat carrier-members e^7 e^8 , Fig. 14^a. The die e^6 is formed with the die-recess e^9 and the extensions e^{10} e^{11} laterally thereof. 10 The stay-seat carrier-members are mounted upon a common rod e^{10} with which is connected a coil-spring e^{11} which tends to normally maintain contact between the lower ends of members e^7 e^8 and the extensions 15 e^9 e^{10} of the die e^6 , but which will allow them to swing toward the housing E' . These lower ends are formed with stay-seat recesses e^{12} which intersect those surfaces of said members e^7 e^8 which are normally in 20 contact with the die-member, and said recesses are also, as shown in Fig. 14, downwardly and rearwardly inclined. The left-hand end, as viewed from the rear of the machine, of each such recess, and as shown 25 in Fig. 14, is outwardly flared, and the two recesses are horizontally alined with each other and with all similar recesses of the other bending devices. This multiplicity of horizontally alined recesses form the 30 stay-seat wherein the stay is held while being bent and after having been inserted therein by the action of the stay-wire feeding-means, as will hereinafter appear.

Each bore e^4 of the bending devices forms 35 a bearing for a plunger E^3 whose rearmost end is provided with two grooves e^{13} e^{14} parallel with the plunger's axis, Fig. 15. To each of these plungers is imparted a reciprocating movement which causes the said rearmost end to intermittently project itself 40 into recess e^5 and across the space occupied by a stay when in position in the stay-seat formed by said recesses e^{12} . The width of the die-recess e^8 is just sufficient to permit 45 the plunger to readily enter therein. Such reciprocating movement therefore forces that portion of the wire of the stay which lies adjacent and opposite the plunger into the die e^6 and into the grooves e^{13} to form 50 bends such as is shown in Fig. 16. This reciprocating movement is imparted to the plunger by providing the front end of each of the latter with an external thread which is engaged by an externally and internally 55 threaded sleeve E^4 , whose external thread is engaged by a nut E^5 suitably fixed to the housing E' , and rotating the sleeve E^4 , the external and internal threads of the latter being of opposite direction as shown. The 60 plungers are suitably splined in their respective bearings in order to prevent rotation thereof during such reciprocating movement, as will be readily understood.

Rotation of the sleeves E^4 is effected by 65 means of shafts E^6 whose rear ends are con-

nected with the sleeves E^4 by means of universal joints, as shown in Figs. 5 and 12. The opposite or front ends of these shafts are each connected with a shaft-portion E^7 by means of a second universal joint. These 70 shaft-portions are each mounted in a hollow rotatable sleeve E^8 itself mounted in a suitable bearing A^2 , Fig. 5, in the frame A , and are splined in such sleeves so as to be slid- 75 able thereon and rotatable therewith. Each sleeve E^8 has secured thereon a bevel-pinion E^{17} which is in mesh with a bevel gear E^{16} . These gears E^{16} are all mounted upon a common shaft E^{11} . The shaft connections 80 between the bending devices and the shaft E^{11} are therefore flexible and extensible and the described movement of the housings E' in the groove a^2 may take place without interfering with the rotation of said connec- 85 tions.

The use of the double-threaded sleeves E^4 is resorted to in order to obtain the required amplitude of reciprocation on the part of plungers E^3 with a comparatively short movement of the sleeves E^4 in the direction 90 of their several axes, and hence with a few turns of the shafts E^6 . The rotation of said shafts E^6 in opposite directions alternately will therefore effect the simultaneous reciprocation of the plungers in the housings E' 95 to perform the bending operation.

The described rotation of shaft E^{11} is obtained through the medium of a cam E^{12} (Fig. 3) mounted upon the transverse shaft B^9 . This cam engages a roller E^{13} (shown 100 in dotted lines in Fig. 3) secured to a yoke E^{14} carrying at its upper end a rack E^{15} . This rack engages a pinion E^{16} (Fig. 1) which is secured to the shaft E^{11} . The reciprocation of the said rack will effect the 105 required rotation of said shaft E^{11} alternately in opposite directions.

The concomitant movement of the bar F' is effected also by the transverse shaft B^9 , through the medium of a cam F^4 mounted 110 thereon. This cam engages a roller F^5 , Fig. 6, mounted upon the lever F^6 , pivoted upon the frame A . This lever articulates with bar F' and its oscillation produces the required reciprocation of the latter to move 115 the housings E' in the groove a^2 , as previously described. Inasmuch as those ends of levers F which articulate with the bars F' and F^2 move through arcs varying from each other, the pivot-pins for these levers 120 are mounted loosely in slots f' formed thereon as shown in Fig. 19, in order to prevent binding of the parts and permit of the required oscillation.

By causing the bending devices to move 125 inwardly toward a common point, I obtain the required change of position on the part of said devices from that occupied at the beginning of the bending operations to that occupied thereby at the end of such opera- 130

tions, within a minimum space, and am thus able to make the machine of minimum width.

The upper end of each die-member E^2 is provided with a roller e^{14} , (Fig. 13) and all of these rollers engage a horizontal groove g formed in a bar G above the bending devices and extending longitudinally of the machine, as shown in Figs. 1, 2 and 6. This bar is carried upon the end of two oscillatory bell-crank $G' G'$, which are, shown clearly in Figs. 3 and 4, and located near opposite sides of the frame and mounted upon standards $h h$ forming a part 15 of a secondary and reciprocable frame H . This frame H is mounted in suitable horizontal and transversely located guideways $a^5 a^5$ extending toward the rear of the machine, as shown in Figs. 3, 4 and 5. Blocks 20 a^6 fixed to frame A , articulate with the lower arms of the bell-crank $G' G'$ as shown, by means of pins $g' g'$ secured to said arms and having bearings in said blocks. By means of this described construction, it will be seen that the frame H in coöperation with said blocks oscillates the cranks $G' G'$; and only at the end of each reciprocatory stroke of said frame. Such oscillation will, therefore, it will be 25 further noted, effect the intermittent upward and downward movement of bar G . The end of each arm of cranks $G' G'$ from which bar G is suspended, articulates with said bar by means of a pin g^8 secured to 30 said bar and a horizontally elongated slot g^4 formed in the said arm, as shown in Figs. 3, 4 and 8, so that the articulation is such as will allow the bell-crank to participate 35 in the reciprocation of the frame H .

40 The reciprocating movement of frame H is derived from the transverse shaft B^9 , through the medium of a cam H' secured to said shaft and arranged to oscillate upon rotation, a lever H^2 pivoted upon the frame 45 and which articulates with a longitudinally placed bar H^8 . This bar articulates with a series of toggles H^4 , one end of each of which articulates with the said frame and the other end of which articulates with a 50 fixed cross-piece A^3 forming part of the main-frame. The stop g^5 is secured to the left-hand end of the machine (Fig. 6) for limiting the feeding movement of the stay-wire as will further appear.

55 *Operation of stay-wire feeding and stay-bending means.*—Let it now be assumed that the transverse shaft B^9 is running and that the bar G has been brought into its uppermost position as illustrated in Fig. 10. In 60 this position of said bar the die-members E^2 are also in a raised position and bring the stay-seat formed by the recesses e^8 in the carriers e^7 , into a horizontal plane passing midway between the two feed-rolls C^5 and C^6 , and therefore in the line of feed of the latter. The operation of cam C to raise the rack C^2 is so timed, that the feed-rolls will begin to revolve and feed the stay-wire as soon as the stay-seat has reached the above-described position, and the throw of 65 the cam is such as to continue the rotation of such rolls long enough to move the stay-wire along a distance sufficient to pass through all of recesses e^8 and a predetermined distance beyond the bending device 70 E which is located at the extreme left of the machine until it strikes the stop g^5 . The cam F^4 is also timed to effect the movement of the bar F' to the left so as to impart to the bending devices that movement 75 along the groove a^2 , which will cause them to spread or recede, that is, cause them to move outwardly away from the central or fixed bending device, and while the feeding operation is taking place. In this raised position of the bar G , frame H will be in its forwardmost position. When said frame is caused to effect its return stroke, bell-crank $G' G'$ will be oscillated so as to move bar G downwardly. This downward movement 80 effects the operation of a suitable cutting device, Fig. 10, whose path of operation intersects the stay-wire, and severs such wire to form a stay. The knife blade J of the cutting device, is preferably mounted as shown 85 in Figs. 8 and 12, so as to articulate with the adjacent bell-crank G' through the medium of a pin g^2 mounted upon the latter and a horizontally elongated slot j' formed in the upper end of said blade. The complementary part J' of the cutting device is 90 suitably fixed to a bracket a^7 secured to the frame A .

The amplitude of the backward movement of the frame is such as to bring the 95 stay-carriers $e^7 e^7$ and hence the stay, to a position opposite the plungers E^3 . The cam E^{12} is timed in a manner such that as soon as the stay is brought to the last described position, the rack E^{14} is raised and 100 the shaft E^{11} rotated in that direction which will effect the backward movement of the plungers E^3 . Simultaneously with the engagement of the said plungers with the stay, cam F^4 moves the lever F^6 so as to move 105 bar F' in the direction opposite that just described, that is to the right, and inauguates the inward or contracting movement of the bending devices. The continued backward movement of the plungers E^3 and 110 contracting movement of the bending devices as a whole, now takes place with the result that a multiplicity of bends are formed in the stay such as have been previously described, the said plungers coöperating with 115 the dies e^6 to this end. This described inward movement of the bending devices therefore compensates for the contraction in 120 overall length experienced by the stay as a result of the formation thereon of the said 125 130

bends and for the consequent change in distances which takes place between those parts of the stay first engaged by the plungers E^3 during the formative period of said bends. 5 As soon as the bends are completed, the bar G again rises as a result of the reengagement of blocks h^2 with pins g' on the bell-crank G', until it again reaches the first described position in which it is ready to receive the stay-wire. 10

It will be noted that when the bar G is in the uppermost position, the bending device on the extreme left (as viewed in Fig. 1, or on the extreme right as viewed in Figs. 15 3 and 10) is removed its maximum distance from the cutting device, and sufficient distance must separate the cutting device from such bending device as will permit the required travel on the part of the latter. This 20 condition being necessary, it is necessary to provide means intermediate of the said two devices for supporting and guiding the stay-wire so as to insure the entrance of its free end into the recess e^{12} in the member e^7 25 nearest the cutting device. Such provision is therefore made and the means for effecting this purpose are most clearly illustrated in Figs. 8, 10 and 11.

The front of the housing a' is formed 30 with a vertical groove a^9 in which slides a block, K attached to the bar G. Passing through this block, parallel with each other and parallel with the direction of feed of the stay-wire, are a plurality of vertically 35 aligned barrels K' in each of which is slidably mounted a rod K^2 . The outer ends of these rods are provided with coil-springs k which are attached to the rods' extremities and to the barrels in a manner such that 40 they will cause the rods to normally project inwardly toward the middle of the machine, as shown. Each rod carries an arm k' , which arms are spaced longitudinally of the machine, and each arm carries a guiding 45 eye h^2 which is in alignment with the stay-seat. These eyes are preferably conical in form and are capable when brought into juxtaposition, of nesting with each other. To insure the rigidity of alignment of these 50 eyes, a horizontal guide-rod k^3 is fixed to the adjacent die-member E^2 and has its outer end mounted in a sliding bearing k^4 secured to block K, and each arm k' is provided with an extension h^5 sliding on this 55 rod.

When the outermost adjacent bending device E, moves outwardly after bar G has reached its uppermost position, as herein previously described, it engages the nearest 60 arm k' and pushes it along in an outward direction until it engages the next arm. All of the arms are finally so moved and against the action of the springs k , until at the end of the travel of device E, they reach a nested position illustrated in dotted lines in

Fig. 10. In this position they are carried slightly beyond a fixed stop a^{10} in the frame A, and upon the subsequent downward movement of bar G and consequently of block K, are carried immediately behind 70 said stop. When the bending device now recedes from the stop, as previously described, the latter holds the arms k' from following it. The subsequent formation of the bends in the stay-wire (which has been 75 previously fed into the machine, severed so as to form a stay and whose extremity has been resting in and been supported by said arms), and the attending contraction thereof causes the said stay-extremity to withdraw from the said arms entirely, whereby the entire stay may be carried 80 downwardly in the machine for further operations, as will further appear. The subsequent upward movement of the bar G effects the release of the arms k' from the stop and permits the coil-springs to return them to their normal position ready for the reception of the stay-wire when moved by the next feeding operation. The device E 85 is preferably provided with a member or extension e^{15} whose path of movement is such as to effect the retrogression of the arms k' as above-described and which is secured in any desired manner thereon. 90

Means for twisting the bends to form loops.—The secondary and reciprocating frame H is formed with a horizontal dovetail slot h^3 (Figs. 5 and 13) which is parallel with the slot a^2 previously described and 100 in which the bending devices rec pccate. In this groove are mounted a multiplicity of twisting devices L uniform in structure and method of operation. These twisting devices correspond in number to the bending devices. Each of these twisting devices excepting the one in the extreme right (which is fixed), is provided with a downwardly projecting fixed bolt m (Fig. 12) passing through a slot h^4 , and through a slot formed 105 in the end of a lever M pivoted to the lower surface of reciprocating frame H, as indicated in dotted lines in Fig. 13. All of these levers M are, as in the case of the previously 110 described levers F, pivoted at different points so that when they are oscillated they will reciprocate the twisting devices in paths of different amplitudes. The rear ends of these levers M all articulate with a common 115 operating bar M' (Figs. 5 and 13) so that 120 they may all oscillate simultaneously in the same direction. The extreme left-hand twisting device has the longest path of movement and this path decreases in length in the different devices successively toward the 125 right, that device next the above-mentioned fixed one having the shortest path. Thus it will be seen that when the bar M' is moved in the direction indicated by the 130 arrows in Figs. 5 and 13, the slidably twist-

ing devices all travel toward the right of the machine and each at the same time decreases its distance from the preceding one. This movement is provided for the same purpose for which it is provided in connection with the bending devices E, that is for the purpose of compensating for the still further contraction in length of the stay which takes place when the bends are twisted 5 to form the loops, and for the concurrent change in distance between the successive bends which results from such twisting operation. This change of distances is, however, slight as compared with the change 10 which takes place during the bending operation, and the maximum length of travel of a twisting device is hence considerably less than that of a bending device. For this reason all of the twisting devices may be 15 and are arranged, as above-described, to travel in the same direction simultaneously. As a result of such arrangement the lever-mechanism is simplified as compared with the arrangement of the lever-mechanism 20 provided for the bending devices, since the compound lever connections used for moving the latter, and herein previously described, are not necessary, as will be readily understood. The reciprocating 25 movement of bar M' is derived from the transverse shaft B⁹ through the medium of a cam M² secured thereto and which engages a roller m secured to one arm of a lever M³ mounted upon the frame A, whose other arm 30 articulates with said bar.

Each twisting device includes a housing L', Figs. 12 and 13, formed with a horizontal bearing l, having its axis parallel with the direction of reciprocation of frame 40 H, and hence parallel with the direction of reciprocation of the plungers E³. Mounted in this bearing is a rotatable twisting-bar L², which is held against endwise movement in the housing L' by a flange 45 l' and a collar l². This bar is provided with a slot l³ in its front end adapted to receive a bend formed by a bending device E, as shown in Fig. 17, and in its rear portion with a bearing l⁴ for a shaft 50 connection l⁵. This connection l⁵ is splined in the bearing so as to be rotatably fixed with reference to but longitudinally slidable in the housing L². Each connection l⁵ articulates with a shaft L⁶, through the 55 medium of universal joint at one end, and at the other end by means of a similar joint and a connection l⁶ rotatably mounted in bearing boxes a¹¹ mounted upon opposite sides of a slot a¹⁰ formed in the cross-piece 60 A³ of frame A, as shown in Fig. 5. Upon each connection l⁶, and between boxes a¹¹ is secured a pinion L⁴. These pinions are all engaged by a rack L⁵ suitably supported so as to be capable of reciprocation. The 65 reciprocation of the rack is derived from

the shaft B⁹ through the medium of a cam L⁶ mounted thereon. This cam engages a roller l⁷ mounted upon one arm of a bell-crank L⁷ whose other arm articulates with the said rack.

70

As also shown in Fig. 12, the bore forming the bearing l⁴ in the twisting-bar L² communicates with a small and parallel bore l⁸ which communicates with slot l³. Secured to the front end of the connection l⁵ is an ejector pin l⁹ which projects through bore l⁸ and into slot l³ when the frame H is in its rearward position. As the said frame H moves forward, these pins withdraw from the slots, for a purpose herein-after described.

75

Operation of the twisting means.—Assuming that the frame H is in its rearmost position, it will be noted, from the previously described connections between said frame and the vertically reciprocating bar G, that the die-members E² are in their lowermost positions. It will now be assumed that these lowermost positions have just been reached. This being the case then, 85 the cam E¹², as before-described, operates to raise rack E¹⁴, rotates the shaft E¹¹, and effects the backward movement of plungers E³ to form the bends. While this bending operation is taking place, the backward 90 movement of frame H is being completed. The cam M², however, is so timed that the levers M will have been actuated so as to cause all of the twisting devices to occupy 95 the position in which they are closest to one another, that is in what I shall call the "contracted" position, when the said frame H is in its forwardmost position. Said cam is furthermore so timed that when the said frame H reaches its rearwardmost position, 100 these devices will have been actuated to spread apart and occupy their "expanded" position. As the frame H moves forward 105 the pins g' g' held by blocks a⁶ a⁶ operate the bell-cranks G' which begin to raise the bar G and hence the die-members E². At this instant the bending operation is completed and the bending devices are in their 110 "contracted" position. By this time the twisting devices will have reached their 115 "expanded" position. In the latter position the distances between the twisting-bars L² is exactly equal to the distance between the plungers E³ and they are also directly opposite one another as shown in Fig. 5. Before the upward movement of bar G begins, the twisting-bars L² will have continued to advance and the plungers E³ moved forwardly, that is in the same direction as said bars L², so as to recede from the stay. These 120 movements, therefore, permit the bends in the stay to enter the slots l³ as shown in Fig. 17, the latter being in this position, unoccupied by the ejector pins l⁹. As soon 125 as these bends are so inserted in the slots, 130

the raising of the bar G will have progressed a distance sufficient to give the twisting devices freedom to move in the slot h³, the stay becoming at the same time disengaged 5 from the carrier-members e¹ e¹. As soon as this occurs the cam M² begins to actuate the levers M through the intermediate connections, and causes them to approach while traveling toward the right of the machine. 10 As soon as this movement is inaugurated, cam L⁶ starts the reciprocating movement of rack L⁵, which rotates the shafts L³, through them the twisting-bars L, and hence the bends themselves. The amount of 15 reciprocation imparted to the rack is such as to turn the said bars through an arc of one hundred and eighty degrees. The twisting operation takes place, therefore, while the twisting devices are approaching each other, 20 whereby the change in distances, herein previously referred to, between the bends is compensated for.

Means for carrying the stays to the crimping means and means for crimping the loops.—As the frame H resumes its rearward movement, ejector pins P⁹ will pass into the slots l³ and eject the twisted loops therefrom. This will allow the stay, which has already been disengaged from carriers e¹ e¹ 25 to be moved downwardly preparatory to being subjected to the crimping operation. Such complete downward movement of the stay is effected by means of a plurality of fingers n n, Figs. 5 and 12, mounted upon 30 an oscillatory shaft N, and the path of operation of whose outer ends intersects the space occupied by the stay while being held in the twisting-bars. Said fingers n n, at the completion of the pins' operation, descend quickly and engage the stay at points thereon between the loops. This action carries the stay from the twisting-bars downwardly into a position for crimping, such as will be presently described.

40 The oscillation of shaft N is derived from shaft B⁹ through the medium of a cam N' mounted thereon, engaging a roller n' mounted upon one arm of a bell-crank n³ pivoted upon the frame A, and whose other 45 arm articulates with the lower end of a rod N². The upper end of said rod articulates with an arm N³, secured to the oscillatory shaft N.

Below the sphere of operation of the 50 bending and twisting devices and secured to the frame A, Fig. 13, are a plurality of crimping-punches O, one such punch being provided for each loop and located vertically below and forwardly of the twisting-bars L², when the latter are in the position which they occupy at the instant of complete ejection of the loops therefrom, as illustrated in Fig. 12. Secured also to the 55 said frame A and adjacent to the crimping-punches O, are depending holders O' piv-

oted as at o and each engaged by a spring-actuated bolt o' seated in the frame and tending to maintain the lower ends of such holders in a backwardly extending position. Each of these holders is formed with a slight horizontal projection o² for arresting the stay. Opposite each holder O' is a spring clip O², secured to the reciprocating frame H, which normally presses against such holder and which has its upper end 70 flared in a backward direction.

Opposite each punch O and secured to the frame H, is a die-block O³ which cooperates with such punch to form the desired crimp in the previously-formed loop, 80 as the said frame moves forward toward the bending devices. The operation of the fingers n n is such as to force the stay between the clips O² and the holders O', as shown in Fig. 12, with the loop extending 85 upwardly and the horizontal portion of the stay resting on the projections o². In this position the loops will be in contact with the punches O. The continued forward movement of the frame H will therefore 90 cause the loops to be pressed into the die-blocks O³ to form the required crimp. During such operation the lower ends of the holders O' will yield by virtue of their engagement with the frame H, as will be 95 readily understood.

In order to give the ends of the fingers n n the required travel, I have also arranged to impart a forward transverse movement to the shaft N. This is accomplished by 100 mounting the ends of said shaft N in slotted bearings a¹⁴, as shown in Figs. 12 and 12^a, and providing yielding fingers n² secured to the shaft and adapted to engage projections a¹³ formed on that part of the frame 105 immediately adjacent to the slotted bearings a¹⁴. The shaft is normally held in the rear portion of said bearings by springs a¹⁵ suitably mounted.

As the rod N² moves downwardly to oscillate the shaft N to move the fingers n n downwardly, such motion continues until the fingers n² strike the projections a¹³, whereupon the farther movement of the said rod causes shaft N to move forwardly in opposition to the action of springs a¹⁵. Farther downward movement of said rod effects a farther downward movement of the fingers n n in opposition to the action of the yielding fingers n². Upon the upward 120 movement of rod N², the reverse of the just-described movements of course take place, as will be readily understood.

Means for carrying the stays to the lock forming means.—Immediately below the 125 crimping means are mounted a plurality of guiding-means which correspond in number and location to the number and location of the crimped loops in the stay. These means each consist of a fixed part P and a part 130

P' capable of reciprocation transversely of the machine and in a horizontal plane, see Figs. 1, 2, 6, 23 and 24. The fixed parts P each consists of two vertical bars p and p' , 5 Fig. 12, fixed respectively to angle-bars a^{16} and a^{17} secured to the frame A, and forming between them a channel for receiving and guiding the loops of the stays in a downward vertical direction. The parts p' 10 of the channel are mounted so as to be reciprocable horizontally and vertically, as will be further more particularly described, whereby they may be brought into the position shown in dotted lines in Fig. 12. In 15 this position the upper ends of parts P' are caused to register with the lower ends of parts P as shown. The parts P' are curved as shown and are each provided with a front horizontally extending portion p^2 . In order 20 to effect the above described registration of these parts P and P' , the parts P' are all mounted upon a carriage P^2 which is reciprocable upon two rods P^3 fixed in supports p^3 forming part of a vertically reciprocable carriage Q mounted in vertical guideways a^{12} , Figs. 3, 5 and 7, formed in the sides of the main frame. This carriage Q, when in its lowermost position, as illustrated in Figs. 7 and 12, rests upon lugs 25 c^{19} forming part of the upright side members of the main-frame A, the contact-positions of said carriage consisting of set-screws q , see also Fig. 6, by means of which proper vertical adjustment may be secured, 30 as will be understood. Mounted upon the lower rear portion of each of the two sides of the carriage Q, is a bell-crank Q' , the upper of whose arms articulate with connecting rods Q^2 , Fig. 7. The articulation 35 of each rod Q^2 with its bell-crank is effected through the medium of a pin q' on said crank, passing through an elongated slot q^2 in the rod. The lower end of each rod Q^2 articulates with the upper arm of a bell- 40 crank Q^3 mounted upon a lower vertically reciprocable cross-head R which, as will be more specifically hereinafter pointed out, 45 operates the keeper bars R' . The lower arm of each bell-crank Q^3 carries a roller q^3 which rides upon the outer surfaces of cams Q^4 and R^3 respectively, and fixed to the 50 driving-shaft B, Figs. 6 and 7. These cams are exactly similar and are formed with a circular portion q^4 upon which the rollers q^3 55 ride immediately after the cross-head R reaches its lowermost position, which is illustrated in said Fig. 7. The said cross-head is provided with two rollers R^2 R^2 , Fig. 8, one of which rides on the cam Q^4 and the other of which rides on cam R^3 . The said shaft therefore, upon rotation, imparts a vertical reciprocating movement to cross-head R. The throw of said cams is such as to permit the cross-head to reach, 60 at the lowermost part of its travel, a point

such that the upper surface of the cross-head will be somewhat lower than, and hence out of contact with, the lower surface of carriage Q, as shown in Fig. 7. In this position of said cross-head and carriage, pin 70 q' will be located in the upper end of slot q^2 .

Mounted upon the lower arm of each bell-crank Q' is a roller q^5 and on the frame portion adjacent thereto and vertically above said roller, is a stop-lug a^{20} . When the 75 cross-head R is in its lowermost position this lug and roller are out of contact as shown.

Formed in the lugs a^{19} and similar lugs a^{21} in the rear thereof, are horizontal bearings for horizontally reciprocating rods T T, Figs. 6 and 7. Fixed to these rods is a cross-bar T' which carries a plurality of upwardly projecting fingers t . These fingers are placed in transverse vertical planes 80 passing between the parts P' and project upwardly into a horizontal plane above that of the horizontal portions p^2 of the guide-parts P' , when the latter are in their lowermost positions. To the forward end of each 85 of these rods, is attached the upper end of a bell-crank T^2 , pivoted to the frame A, the lower arms of which carry rollers t' traveling respectively in grooves t^2 of two cams T^3 fixed to shaft B, Fig. 6. These grooves 90 are so formed that when cross-head R is in its lower-most position, the cross-bar T' and hence fingers t , will be in their forward-most position. When the fingers t are in the above described position, a stay-wire 95 laid against and in front of them will be brought vertically beneath the clamping devices U, which in their general construction and operation are substantially identical with the clamping devices shown and described in the above-mentioned Patent No. 689,430.

Extending longitudinally, above the parts P', Figs. 12, 23 and 24 and secured to the carriage p^2 is an angle-bar P^4 upon which are fixed bearing-boxes p^4 p^4 in which are mounted the ends of a horizontal and longitudinally extending oscillatory shaft P^5 . Fixed to this shaft is a plurality of backwardly extending fingers p^5 p^5 , whose paths of oscillation extend between parts P' , as will be seen from an inspection of Figs. 23 and 24. One end of this shaft, the left-hand end as shown, extends through an opening a^{18} in the frame, Fig. 4, and has secured to such end a sprocket wheel P^6 . Over this wheel passes a sprocket-chain P^7 which has an end secured to a spring p^6 which is itself secured, as at a^{23} , to the frame A. The other end of said chain is secured to one arm of a lever P^8 whose other arm lies in the path of revolution of a roller b^4 mounted upon the gear B' , as shown in dotted lines in Fig. 4. The axis of shaft P^5 coincides with the axis of curvature of the parts 100 105 110 115 120 125 130

P' , which curvature is made circular, and the distance from this axis to the ends of fingers p^5 p^5 is made such that the said ends will strike, during their downward movement, a stay lying in the channel of said parts P' .

Upon the inside of each of the two side members of frame A is formed a vertical guiding-rib a^{22} on each of which slides a 10 guiding member V' of a carriage V which includes a longitudinally placed horizontal bar V^2 . This bar is provided at its ends with trunnions v mounted in suitable bearings v' formed in members V' so that it may 15 oscillate. Such oscillation, is, however, limited by a lug v^4 and two set-screws v^2 and v^3 mounted upon each member V' , Figs. 12 and 12^a. Secured to this bar is a multiplicity of 20 forwardly-extending fingers V^3 each formed with a hook at its upper end. These fingers lie in vertical planes passing between the 25 guiding members P and P' , and are of dimensions such that when the bar V^2 is tilted so as to cause lug v^4 to engage the upper set screw v^2 , the path of movement of the hooked ends of the fingers will intersect a stay lying in the channel between bars p and p' . When 30 the said lug engages the other set screw v^3 the upper ends of the fingers will lie in a vertical plane back of and parallel with a stay which is occupying its position between the 35 holders O' and spring clips O^2 , as shown in dotted lines in Fig. 12.

A vertical operating rod V^4 articulates 35 with the bar V^2 forwardly of the latter's axis and has secured to its lower end a rack V^5 . This rack is engaged by a gear V^6 secured to a shaft V^7 upon which is secured a pinion V^8 . A gear-segment V^9 is mounted 40 upon a frame member A^5 Fig. 7, and engages said pinion V^8 . This segment has secured to it a forwardly extending arm v^3 carrying a roller v^4 which travels in a groove v^5 formed in a cam V^{10} secured to the 45 driving shaft B, Fig. 6.

Operation of means for carrying the stays.—It will now be assumed that the parts are in the position illustrated in Fig. 7. Rotation of shaft B in the direction indicated by the arrow, will cause cams Q^4 and R^3 to engage the rollers R^2 to raise the cross-head R. This upward movement continues until the latter engages the carriage Q whereupon this latter carriage is also raised, 55 carrying with it the carriage P^2 . At about the time the carriage Q is first engaged by cross-head R, the upper ends of the keeper-bars R' reach a horizontal plane passing through the horizontal guide-ways of the 60 guide portions p^2 . Also at about this time the lower arm of bell-crank Q' strikes the lug a^{20} and a continued upward movement of carriage Q causes the upper arm of bell-crank Q' to quickly move the carriage P^2 65 into its rearmost position, in which the up-

per ends of the guideways in guide-parts P' , will fall vertically beneath the lower ends of the guide-ways in guide-parts P. This upward movement continues until the guide-parts reach the position shown in dotted 70 lines in Fig. 12. Cam V^{10} is so timed that

while the above described movements are taking place, the rack will have been moved upwardly to push carriage V upwardly and place fingers V^3 in the position shown in 75 dotted lines in said Fig. 12. At the time these fingers have reached such described position a crimping operation will have been completed and the frame H will have moved 80 backwardly. While these movements of the lower guide-part and the carriage V have been imparted, the bell-crank T^2 will have been actuated by cam T^3 to throw the bar T' backwardly, carrying with it the fingers t , which latter reach a position shown in dotted 85 lines in Fig. 12. By the time these above-described positions have been assumed a clamping operation will have been effected by the clamping devices U, as will be further described, and the cams Q^4 and R^3 will 90 have reached a point in their rotation, such that further rotation will permit the cross-head R and carriage Q to move downwardly by gravity. Such downward movement takes place, but just before such event, cam 95 V^{10} quickly actuates segment V^9 to actuate rod V^4 to first tilt bar V^2 to throw fingers V^3 over the stay held between holders O' and clips O^2 , and then quickly pull all the fingers 100 downwardly and carry the loops of said stay through the guideway of part P into the upper portion of part P' . This action is immediately followed by the engagement of roller b^4 with the lever P^8 , resulting in the quick downward pulling and the relaxation 105 of chain P^7 and the consequent quick downward movement and return of the fingers p^5 p^5 . The latter carry said stay through the curved portion of guide-parts P' to the 110 rear of the horizontal portions thereof and in a vertical plane in front of fingers t t , return movement of said fingers being effected by spring p^6 . As soon as these movements are completed, the said cross-head R and carriage Q start on their downward path 115 and shortly thereafter cam Q^4 actuates bell-crank Q' to throw the carriage P^2 forwardly. Shortly after, cam T^3 actuates bell-crank T^2 to move fingers t forwardly. In the course 120 of such forward movement, the carriage Q will have reached a lower position such as will bring the stay carried in guide-part P' , into the path of movement of said fingers t . By the time the latter will have completed their forward movement, the carriage Q will 125 have been brought to rest on lugs a^{19} and the stay will have been brought directly beneath the clamping devices U, as shown in Fig. 12, by the fingers t .

As will be further described, the interme- 130

diate line-wires W pass through the guide-parts P' so that the said loops are laid upon same as a result of the above described movements. The fingers t carry the stay forwardly beyond the end of the lower portions of guide-parts P' , and in order to hold it in place pending the engagement therewith of the keeper-bars R' , the upper-portion of the said guide-parts is extended as at p' .

10 *Means for effecting engagement of line wires and stays to form locks.*—These means are, as previously mentioned, substantially the same as the clamping or locking devices shown and described in the above-mentioned Patent No. 689,430, each comprising a clamping block U' , a pair of clamping-jaws U^2 and U^3 , actuated respectively by oscillatory arms U^4 and U^5 , which articulate with a front longitudinally extending bar U^6 , Fig. 6, and a similar back bar U^7 , Fig. 2. Bar U^6 is connected with a bell-crank U^8 articulating with a vertically movable rod U^9 having a strap u at its lower end articulating with an oscillatory counter-weighted lever U^{10} , Fig. 4, pivoted at a^{24} on frame A. A roller u' is mounted upon said lever U^{10} and is engaged by a cam b^5 secured to shaft B.

Bar U^7 is connected with a bell-crank U^{11} articulating with a vertically movable rod U^{12} , Fig. 2, whose lower end articulates with a counterweighted lever U^{13} , Fig. 3. This lever is pivoted at a^{25} to the frame A, and carries a roller u^2 engaged by a cam b^6 secured to shaft B. It will therefore be seen that rotation of said shaft B will effect the operation of the clamping-jaws U^2 and U^3 , the cams b^5 and b^6 being, of course, timed so as to effect the clamping at the proper time.

45 The upper ends of the keeper-bars R' are constructed in accordance with the description contained in said above named patent and hence need not be further described herein.

In order to render the clamping-die u^3 Figs. 28 and 29, adjustable in a vertical direction so as to secure its proper coöperation with the clamping jaws, I provide a transverse bore u^4 above each such die in which slides a member u^5 provided with an inclined seat u^6 for receiving the upper inclined portion of the die u^3 . The ends of the bore are threaded and set screws u^7 u^7 engage these threads and the ends of said member u^5 . By shifting the latter endwise and locking same by means of said screws, it will be seen that vertical adjustment of said die may be obtained. The carriages Q and R are preferably counter-weighted as shown and as will be readily understood.

60 *Means for feeding the line wires.*—Located at the back and longitudinally of the machine is a horizontal shaft W' mounted in suitable bearings fixed to the frame.

Upon this shaft are secured the grooved guiding-wheels W^2 corresponding in number and location with the line-wires W , as shown in Fig. 2, and around which such wires are wrapped in the usual manner. In 70 transverse alinement with each wheel W^2 , is a tension device, mounted upon a fixed bar W^3 . Each of these devices comprises in its structure a main member u , which is fixed to said bar W^3 , and a vertically movable member w' pivoted to member w at w^2 , as shown in Fig. 9. A number of grooved tension-rollers w^3 are mounted upon member w , and similar complementary rollers are mounted upon member w' , these two 80 sets of rollers forming a groove for the reception of the line-wire. Bearing upon the top surface of member w' is a cam w^4 , fixed to an oscillatory shaft W^4 mounted in standards w^5 formed on the main members w . 85 One end of the shaft is provided with a counterweight w^6 which hence presses the upper set of rollers down upon the wire and the latter against the lower set of rollers.

The line-wires, after leaving the vicinity 90 of the lock-forming means, pass under a horizontal roller W^5 , at the front and extending longitudinally between the two side members of the frame A, as shown in Fig. 7. In front of this roller and parallel therewith, is a rotary shaft W^6 upon which are fixed the feed-wheels W^7 formed with the teeth w^7 . This shaft has rotatably mounted thereon the pinion w^8 which is engaged by the gear segment W^8 , Fig. 3. This segment 100 is pivoted upon the frame A and has fixedly connected therewith an arm W^9 articulating with a vertically movable rod W^{10} , the lower end of which articulates with a counter-weighted lever W^{11} , also pivoted on frame 105 A. This lever has formed upon it a cam surface lying in the path of rotation of a roller b^8 mounted upon a disk b^9 , Fig. 30, secured to shaft B. The pinion w^8 is fixedly connected with a ratchet-wheel W^{12} , Fig. 7, 110 which is engaged by a pawl w^9 mounted upon a disk w^{10} fixed to shaft W^6 . It will therefore be seen that the oscillation of the lever W^{11} resulting from the rotation of shaft B, will effect an intermittent rotary 115 movement of the feed-wheels W^7 , in the direction indicated by the arrow in Fig. 3.

In order to vary the throw of the segment W^8 , its articulation with the upper end of rod W^{10} is made adjustable as shown in 120 said Fig. 3.

Below the feed-wheels W^7 , is rotatably mounted the winding-reel Y, whose shaft Y^3 extends to the right and is connected with a sprocket pinion y loosely mounted upon said 125 shaft, by means of a friction clutch Y' , one of whose members is fixedly secured to the said pinion and the other of whose members is fixedly secured to said shaft. The pinion y is driven by a sprocket-chain y' , passing 130

over a sprocket-wheel Y^2 fixed to shaft B, as illustrated in Fig. 3.

The two clutch-members are in constant engagement, but the frictional engagement between them is made such that when the fence is held by the feed-wheels W^7 , when the latter are stationary (during the inoperative movement of segment W^8 and also by the clamping jaws during the clamping 10 operation) said clutch-members slip and the shaft Y^3 is hence not rotated. As soon, however, as the fence is free to move and the feed-wheels are actuated, the clutch becomes operative and the reel winds up that 15 portion of the fence fed from the feed-wheels. Inasmuch as the frictional engagement of the two clutch-members becomes operative throughout a small portion of the rotary movement of pinion y , and the constant 20 engagement of such two members would hence entail a considerable loss of power, I have provided means for avoiding this condition. To this end I have connected that clutch member which is secured to the reel, with a spring-actuated shifting arm 25 y^2 , Fig. 1, which tends to keep the said two members in constant engagement. Bearing against said arm is a cam y^3 , Fig. 1, mounted upon an oscillatory rod y^4 , Fig. 30, provided with an arm y^5 lying in the path of rotation of an elongated cam-surface b^{10} fixed to the inside surface of disk b^9 . This cam surface is of a length such that it holds rod y^4 in a position in which cam y^3 will effect 30 the disengagement of the two clutch members, during such time as such disengagement is accomplishing no useful purpose. Just prior to the time that it is desired to effect one of the intermittent movements of 35 the reel, cam-surface b^8 releases the shifting arm y^2 and permits the clutch-members to engage. This engagement is allowed to continue until after such intermittent movement of the feed-wheels is completed.

40 The described means for actuating the feeding means, is so timed, that the forward feeding movement will take place immediately upon arrival of the carriage Q at a point in the downward stroke such as will 45 permit the stays to clear the locking devices when the line wires are fed forward.

In order to maintain a required tension 50 on the fence between the feed-wheels W^7 and the reel Y , I provide a heavy roller Z, Figs. 1 and 7, which is mounted upon the ends of two arms z^2 which are loosely pivoted upon the shaft W^6 , such roller extending across and resting against the fence, as shown. To provide against the feed-wheels 55 W^7 moving in the reverse direction, the shaft W^6 has fixed thereto at its left hand end, Fig. 5, a ratchet-wheel W^{14} engaged by a pawl a^{31} mounted upon the frame A and adjacent thereto, as will be understood.

60 65 *Means for winding the stay-wires.*—In

addition to the line-wires operated upon, as above described, and locked to the stays, two additional line-wires W^{12} are caused to pass through the machine simultaneously with the nine line-wires W illustrated, for forming the upper and lower finishing line-wires upon which the extremities of the stays are wound as illustrated in Fig. 34. These two line-wires are, as will be understood, not acted upon by the locking means, but pass over feed-wheels W^2 at the back of the machine, and over feed-wheels W^7 at the front thereof. The wheels are so placed that such line-wires pass beneath the stays after the latter have been locked to the intermediate 70 line-wires, so that the said stays extend laterally beyond the two outer or finishing wires, one of such extending stay ends being illustrated in Fig. 31. In the line of feed of each of these finishing wires W^{12} , Fig. 1, 75 is a threaded winding member X, rotatably mounted in a hanger a^{28} depending from the main-frame A and having its axis parallel with such line of feed. This member is formed with a V-shaped slot x passing 80 through its axis whereby said wire may pass therethrough and have its axis coincide with the axis of said member, as shown in Fig. 32. Forming a part of the front end of the member X is a pinion x' meshing with a 85 gear x^2 fixed to a spindle x^3 upon which is secured a pinion x^4 , Fig. 33. These pinions x^4 are both engaged by a rack X' which is provided at its outer right-hand end with a yoke X^2 straddling shaft B^9 . This yoke 90 carries a roller x^5 traveling in the groove of a cam X^3 fixed to said shaft B^9 . Rotation of the latter therefore reciprocates the rack X' and effects the alternate opposite 95 rotation of the winding members X, as will 100 be understood.

The winding devices are furthermore so placed, that when the stays have been placed in position upon the intermediate line-wires ready for the operation of the locking device 110 U, the projecting ends of the stays will fall vertically below grooved rollers x^6 mounted upon the back of member X, when the latter are in their rearmost position, as illustrated in dotted lines in Fig. 32. Secured to hanger 115 a^{28} and vertically above each such stay-position, are two supports a^{29} having their lower extremities formed with grooves a^{30} for receiving such stay ends at a point somewhat in the rear of members X, as shown in Fig. 120 32. Mounted upon carriage R are two keepers r, Fig. 6, which are placed vertically beneath supports a^{29} and are provided with the V-shaped slots r' for receiving the line-wires W^{12} W^{13} . When member X is in its 125 said rearmost position, the slot x is down, and the thread in such member has a pitch substantially equal to the diameter of the stays.

Operation of the winding means.—As- 130

suming that a stay is about to be raised and secured to the intermediate line-wires by the locking devices, said stay-wire ends are then in a position immediately below the wind-
 5 ing-devices. Upon the upward stroke of cross-head R keeper-bars r raise the line-wires W^{13} and with them the stay, at the same time that the intermediate line-wires and the stay are raised for subjection to the
 10 locking operation. This movement brings the free stay-ends up against the supports a^{29} and into grooves a^{30} , the said line-wires W^{13} W^{13} being simultaneously raised and placed in the slot α of member X. In the
 15 raised position the free stay-ends lie in the grooves of rollers x^6 . As soon as this position has been reached, cam X^3 becomes operative and rotates the train of gears connected with member X, so as to rotate the
 20 latter in a direction such that its threads will carry it forward while the rollers x^6 are revolving about the axes of the wires W^{13} W^{13} . This revolution of said rollers causes
 25 the free stay-ends to wind about said line-wires W^{13} as shown in Fig. 32, the forward travel of the member X permitting the folds of the wire to succeed each other as will be understood.

On the downward movement of cross-head 30 R, and after the locking operation as well as the winding operation has been completed, the line and stay-wires drop downwardly a distance sufficient not only to permit the stay to clear the locking devices but
 35 also to allow the line-wires W^{13} W^{13} to drop down out of slots α , and the stay to thus clear the winding devices. The forward feeding movement of the fence, which now follows is hence not interfered with.

40 The gearing between shaft B^9 and the main driving shaft B is such that each complete revolution of said shaft B will be accompanied by one complete revolution of said shaft B^9 . One of each of all the above-
 45 described complete operations therefore takes place for each complete revolution of shaft B.

In order to cause the twisting operation to subject the wire to the least possible 50 strain, I place the twisting devices in a position such that, when the bends are about to enter and are entering the slots l^2 , the axis of each twisting-bar L^2 will coincide with the axis of one side of the corresponding
 55 loop, Fig. 17, so that the latter will be eccentric relatively to such bar axis, and will hence revolve about such loop-side axis.

Having fully described my invention, what I claim and desire to secure by Letters
 60 Patent is:

1. In a wire-fence machine, the combination of means for intermittently feeding a stay-wire; means for intermittently severing such wire to form stays; means for bending such a stay at intervals therealong;

means for twisting such bends to form loops; means for crimping said loops; means for feeding a plurality of line-wires; means for carrying said stay from said bending and twisting-means to said crimping-means; 70 means for carrying said stay from the latter into juxtaposition with and transversely of said line-wires; and means for effecting engagement between the latter and said loops to form locks. 75

2. In a wire-fence machine, the combination of means for holding a stay; a plurality of plungers disposed at intervals along, reciprocable transversely with respect to said stay and movable in the longitudinal direction of the latter; a die disposed opposite and coöperating with each plunger and placed on the side of said stay opposite that occupied by such plunger; each plunger and die when coöperating being adapted to form 80 a bend in said stay; means for imparting such longitudinal movement to said plungers; and means for reciprocating the latter. 85

3. In a wire-fence machine, the combination of means for holding a stay; a plurality of plungers disposed at intervals along and reciprocable transversely with respect to said stay, and reciprocable in the longitudinal direction of the latter; a die disposed opposite and coöperating with 90 each plunger and placed upon the side of such stay opposite that occupied by such plunger; each plunger and die being adapted, when coöperating, to form a bend in said stay; and means for imparting said reciprocating movements to said plungers. 100

4. In a wire-fence machine, the combination of means for holding a stay; a plurality of movable means disposed at intervals along the latter while being held, each 105 adapted to form a bend therein; and means for effecting the movement of said bending-means during the bending operation so as to lessen the distance therebetween, whereby the contraction in length on the part of such 110 stay is compensated for.

5. In a wire-fence machine, the combination of means for holding a stay; a plurality of means reciprocable in the longitudinal direction of said stay, each adapted to form 115 a bend therein; and means for effecting the reciprocation of each of said bending-means in degrees varying as the variation in distance between the corresponding bends at the beginning and at the end of their respective formations. 120

6. In a wire-fence machine, the combination of a suitable frame; a plurality of aligned bending devices slidably mounted upon said frame, each comprising a plunger, 125 a plunger-housing and a die-member reciprocable on said housing and at right angles with respect to the direction of reciprocation of said plunger; said die-members provided with aligned recesses together forming 130

a seat for a stay parallel with the direction of reciprocation of said bending devices; means for intermittently feeding a stay-wire in such last-named direction of reciprocation; means for reciprocating said die-members so as to alternately bring said stay-seat in alinement with said feeding-means and in the path of operation of said plunger-housings and adapted to alter the distance 10 between adjacent housings during the bending operations; and means for reciprocating said plungers; the direction of such plunger-reciprocations being at right angles with respect to the direction of reciprocation of 15 said housings and said die-members.

7. In a wire-fence machine, the combination of a suitable frame; a plurality of alined bending devices slidably mounted upon said frame and comprising a reciprocable plunger, a plunger-housing and a die-member reciprocable in said housing and at right angles with respect to the direction of reciprocation of said plunger; each such die-member provided with a yielding-member; 20 said yielding-members provided with recesses forming a seat for a stay parallel with the direction of reciprocation of said bending devices; means for intermittently feeding a stay-wire in said last-named direction of 25 reciprocation; means for reciprocating said die-members so as to alternately bring said stay-seat in alinement with said feeding-means and in the path of operation of said 30 plungers; means for reciprocating said 35 plunger-housings and adapted to alter the distance between adjacent housings during the bending operations; and means for reciprocating said plungers, the direction of such plunger reciprocation being at right 40 angles with respect to the direction of reciprocation of said housings and said die-members.

8. In a wire-fence machine, the combination of a suitable frame; a plurality of 45 alined bending devices slidably mounted upon said frame, each comprising a plunger, a plunger-housing and a die-member reciprocable in said housing and at right angles with respect to the direction of said 50 plunger; said die-member provided with alined recesses together forming a seat for a stay parallel with the direction of reciprocation of said bending devices; means for intermittently feeding a stay-wire in the direction of reciprocation of said bending 55 means and in the path of operation of said plungers and adapted to alter the distance between adjacent housings during the bending operations; a bar for reciprocating said 60 die-members, the amplitude of reciprocation of said bar being such as to alternately bring said stay-seat in alinement with said feeding-means and said plungers; and means for reciprocating said plungers; the direction of such plunger-reciprocation being at 65

right angles with respect to the direction of the reciprocation of said housings and die-members.

9. In a wire-fence machine, the combination of a suitable frame; a plurality of alined bending devices slidably mounted upon said frame and comprising a reciprocable plunger, a plunger-housing and a die-member reciprocable in said housing and at right angles with respect to the direction of reciprocation of said plunger; each such die-member provided with a yielding-member; said yielding-members being provided with recesses forming a seat for a stay parallel with the direction of reciprocation of said 70 bending devices; means for intermittently feeding a stay-wire in said last named direction of reciprocation; a reciprocating bar with which each of said die members is slidably connected and adapted to effect the 75 reciprocation of said die members in said housings; the amplitude of reciprocation of said bar being such as to alternately bring said stay-seat in alinement with said feeding means and in the path of operation of said 80 plungers; means for reciprocating said plunger-housings on the frame and adapted to alter the distance between adjacent housings during the bending operations; and means for reciprocating said plungers, the 85 direction of such plunger-reciprocations being at right angles with respect to the direction of reciprocation of said housings and die-members.

10. In a wire-fence machine, the combination of means for holding a stay; a plurality of movable means disposed at intervals along said stay while the latter is being held, each adapted to form a bend therein; means for moving each such bending means in the 100 longitudinal direction of said stay; means for actuating said bending-means during such longitudinal movement to effect the bending operations; twisting-means having a similar longitudinal movement, reciprocable relatively to said bending-means, 105 adapted to engage the bends formed by the latter and twist same to form loops.

11. In a wire-fence machine, the combination of means for holding a stay; a plurality of movable means disposed at intervals along said stay while the latter is being held, each adapted to form a bend therein; means for moving each such bending-means in the longitudinal direction of said stay; 110 means for simultaneously actuating said bending-means during such longitudinal movement to effect the bending operations; twisting-means having a similar longitudinal movement, reciprocable relatively to said bending-means, adapted to engage the bends formed by the latter and twist same to form loops.

12. In a wire-fence machine, the combination of means for holding a stay; a plu- 115

- rality of movable means for holding a stay; a plurality of movable means disposed at intervals along said stay while the latter is being held, each adapted to form a bend there-
 5 in; means for moving each such bending-
 means in the longitudinal direction of said stay; means for simultaneously actuating said bending-means during such longitudinal movement to effect the bending oper-
 10 ations; and twisting-means having a similar longitudinal movement, reciprocable relatively to said bending-means, adapted to engage said bend and twist same simultaneously to form loops.
- 15 13. In a wire-fence machine, the combination of means for holding a stay; a plurality of plungers disposed at intervals along and reciprocable transversely with respect to said stay, and reciprocable in the 20 longitudinal direction of the latter; a die disposed opposite and coöperating with each plunger and placed upon the side of such stay opposite that occupied by such plunger; each plunger and die being adapted when 25 coöperating to form a bend in said stay; means for imparting the reciprocating movement to said plungers; and means for engaging the bends so formed and twisting same to form loops.
- 30 14. In a wire-fence machine, the combination of means for holding a stay; a plurality of plungers disposed at intervals along and reciprocable transversely with respect to said stay, and reciprocable in the 35 longitudinal direction of the latter; a die disposed opposite and coöperating with each plunger and placed upon the side of such stay opposite that occupied by such plunger; each plunger and die being adapted 40 when coöperating to form a bend in said stay; means for imparting the reciprocating movement to said plungers; means for engaging the bends so formed and twisting same to form loops; said twisting means being also movable in the longitudinal direction of said stay; and means for effecting such movement during the twisting operation.
15. In a wire-fence machine, the combination of means for holding a stay; a plurality of movable means disposed at intervals along the latter while being held, each adapted to form a bend therein; means for effecting the movement of said bending-
 55 means during the bending operation so as to lessen the distance therebetween, whereby the contraction in length on the part of such stay is compensated for; means also movable in the longitudinal direction of said stay, 60 adapted to engage the bends so formed and twist same to form loops; and means for imparting such movement to said twisting-means.
16. In a wire-fence machine, the combination of means for holding a stay; a plurality
- of means reciprocable in the longitudinal direction of said stay, each adapted to form a bend therein; means for effecting the reciprocation of each of said bending means in degrees varying in distance between the corresponding bends at the beginning and at the end of their respective formations, whereby said bending operations may be formed simultaneously; means also reciprocable in the longitudinal direction of said stay adapted to engage the bends so formed and twist same to form loops; and means for effecting the reciprocation of such twisting-means in degrees varying as the variation in distance between the corresponding twists at the beginning and at the end of their respective formations.
17. In a wire-fence machine, stay-bending means comprising the combination of a housing; a plunger reciprocably mounted in said housing but fixed against rotation therein; a die located in the path of operation of said plunger; a stay-seat passing transversely to the direction of plunger-operation and located between said plunger and die; the said plunger being provided with a thread; an interiorly and exteriorly threaded sleeve, the interior thread of which engages the thread on said plunger; a fixed nut engaged by the exterior thread of said sleeve; and means for rotating said sleeve.
18. In a wire-fence machine, the combination of means for forming a plurality of bends at intervals along a stay: means for holding said stay after being so formed; and means coöperating with said holding-means for twisting said bends simultaneously and comprising a plurality of individual twisting devices movable in the direction of said stay; and means for effecting such movement during the twisting operation so as to compensate for the contraction in the stay's length incident thereto.
19. In a wire-fence machine, twisting means comprising the combination of a suitable frame; a sliding-member mounted upon said frame; a rotatable twisting-bar mounted in said member; and an extensible shaft connected with said bar; the axis of the latter being transverse with respect to the direction of sliding movement of said member.
20. In a wire-fence machine, twisting means comprising the combination of a suitable frame; a sliding-member mounted upon said frame; a rotatable twisting-bar mounted in said member; an extensible shaft connected with said bar; the axis of the latter being transverse with respect to the direction of sliding movement of said member; means for imparting such sliding movement, 125 and for simultaneously rotating said shaft.
21. In a wire-fence machine, twisting means comprising the combination of a suitable frame; a plurality of sliding-members mounted upon said frame; a rotatable twist- 130

- ing-bar mounted in each of said members; an extensible shaft connected with each of said bars; the axes of the latter being transverse with respect to the direction of sliding movement of said members; means for imparting to each of said sliding-members a movement of different amplitude; and means for simultaneously rotating said twisting-bars.
- 10 22. In a wire-fence machine, twisting-means comprising the combination of a suitable frame; a sliding-member mounted upon said frame; a rotatable twisting-bar mounted in said member, and provided with a slot 5 in its extremity adapted to receive a bend in a stay; an extensible shaft connected with said bar; the axis of the latter being transverse with respect to the direction of sliding movement of said member.
- 15 23. In a wire-fence machine, twisting-means comprising the combination of a suitable frame; a rotatable twisting-bar mounted in said member provided with an end slot 10 adapted to receive a bend in a stay, and having an axial bore; a shaft slidable within said bore but rotatably fixed with relation thereto; said bar being provided further with a passage between said bore and slot; and an ejector pin secured to said shaft and 15 slidable in said passage, said pin being of a length such that it may project into said slot.
- 20 24. In a wire-fence machine, twisting-means comprising the combination of a suitable frame; a plurality of sliding-members 25 mounted upon said frame; a rotatable twisting-bar mounted in each of said members; an extensible shaft connected with each of said bars; the axis of each of the latter being transverse to the direction of sliding movement of said members; means for imparting to each of said sliding members a 30 sliding movement of different amplitude; and means for intermittently and simultaneously rotating said bars.
- 25 25. In a wire-fence machine, twisting-means comprising the combination of a suitable frame; a plurality of members mounted upon said frame and reciprocable in the same direction thereon; a rotatable twisting-bar mounted in each of said reciprocating-members; an extensible shaft connected with each of said bars; the axes of the latter being transverse with respect to the direction of reciprocating movement of said members; 35 means for effecting reciprocation of each of said members and of varying amplitudes; and means for simultaneously rotating said bars during a part of the reciprocating movement of said members.
- 30 26. In a wire-fence machine, wire-guiding means comprising the combination of a suitable frame; a plurality of parallel bars mounted in said frame; springs connected with said bars and adapted to maintain same 40 in a normal position; and an arm secured to each such bar, and formed with a wire seat, the seats in the different bars being in alignment with each other, such direction of alignment being parallel with the direction of the feeding of the wire; and means for reciprocating said frame so as to intermittently bring said seats into the path of feeding movement of such wire.
- 45 27. In a wire-fence machine, the combination of means for feeding a wire in the direction of its axis; means reciprocable in such direction, located in the line of such feed, and adapted to form a bend in such wire; and means intermediate of such feeding and bending means for supporting said wire during its travel therebetween.
- 50 28. In a wire-fence machine, the combination of means for feeding a wire in the direction of its axis; means reciprocable in such direction, located in the line of such feed, and adapted to form a bend in such wire; yielding means intermediate of such feeding and bending means for supporting said wire during its travel therebetween.
- 55 29. In a wire-fence machine, the combination of means for feeding a wire in the direction of its axis; means reciprocable in such direction, located in the line of such feed, and adapted to form a bend in such wire; and a plurality of yielding supports 60 located intermediately of such feeding and bending means for supporting said wire during its travel therebetween.
- 60 30. In a wire-fence machine, the combination of means for feeding a wire in the direction of its axis; means located in the line of such feed, and adapted to form a bend in such wire; and means intermediate of such feeding and bending means for supporting said wire during its travel therebetween.
- 65 31. In a wire-fence machine, the combination of means for feeding a wire in the direction of its axis; a carrier for receiving the wire so fed; means for severing such wire to form a stay; means associated with said carrier for forming a plurality of bends on such stay at intervals therealong and movable in the direction of such feed; means intermediate of said feeding-means and carrier for guiding said stay, capable of yielding in the direction of movement of said bending-means and in the path of movement of the latter, whereby such yielding-means may be moved toward said feeding-means; and means for holding said guiding-means 70 in position after such last described movement, during a part of the movement of said bending-means.
- 70 32. In a wire-fence machine, the combination of means for feeding a wire in the direction of its axis; a carrier for receiving the wire so fed; means for severing such wire to form a stay; means associated with

- 5 said carrier for forming a plurality of bends on said stay at intervals therealong and reciprocable in the direction of such feed; guiding-means intermediate of said feeding-
means and carrier capable of yielding in the direction of reciprocation of said carrier and located in the path of reciprocation of the latter whereby said yielding-means may be moved toward said feeding-means during
10 one reciprocating stroke of the carrier; and means for holding such yielding-means in a position resulting from said last-described movement during the other reciprocating stroke of said carrier.
- 15 33. In a wire-fence machine, the combination of means for holding a stay; bending-means for forming a plurality of bends at intervals along such stay and movable in the longitudinal direction of said stay; means for moving said bending means during the bending operation so as to compensate for the change of relationship along said stay on the part of the bends so formed; means for guiding the end of such stay projecting from the bending-means, and capable of yielding in a direction away from the bending-means; means for engaging said guiding-means to move same in said direction; and means for holding same in a position imparted thereto by such movement during the bending operation, whereby such projecting end may become disengaged from said guiding means.
34. In a wire-fence machine, the combination with a bending device adapted to form a bend in a stay and including in its structure a reciprocable plunger; of a twisting device disposed opposite said plunger including in its structure a rotatable bar reciprocable toward and from said plunger and having a bend-receiving slot in its end; said plunger and bar co-operating with each other so as to cause such bend to enter said slot; the axis of the latter being eccentric relatively to the axis of said plunger.
35. In a wire-fence machine, the combination of a suitable frame; a plurality of aligned bending devices mounted to reciprocate horizontally upon said frame each including a housing and a carrier reciprocable vertically thereon, a secondary frame horizontally reciprocable toward and from said bending devices and in a direction transverse with respect to the latter; a plurality of twisting devices mounted to reciprocate horizontally upon said secondary frame and in a direction parallel with the direction of reciprocation of said bending devices; means for effecting the reciprocation of said secondary frame; and means connecting the latter with said carriers whereby such carriers and frame are simultaneously reciprocated.
36. In a wire-fence machine, the combination of means for forming stays; means below and horizontally removed from said stay-forming means for securing such stays to line-wires; and means for carrying such stays from the said forming to the securing means including a guide having a part thereof fixedly mounted below said forming-means, a movable carriage, a part of said guide being mounted upon said carriage, means for moving said carriage to effect the alternate registration of said two guide-parts and the bringing of said second-named guide-part into the proximity to said securing-means, and means for moving a stay through said guide and out of the latter.
37. In a wire-fence machine, the combination of a vertical fixed guide-part; a horizontally and vertically reciprocable guide-part having one portion extending upwardly and another portion extending horizontally; and means for effecting the horizontal and vertical reciprocation of said last-named guide-part so as to bring its vertical portion into registration with the lower end of said fixed guide-part.
38. In a wire-fence machine, the combination of means for feeding a stay-wire in the direction of its axis; carrying means for receiving the wire so fed; means for severing such wire to form a stay; means below the fine of such feed for forming a plurality of bends at intervals along such stay; means for twisting the bends so formed; means for crimping such bends and located below said bending-means; means for carrying such stay to said crimping means; clamping means for effecting the union of said bends with a line-wire; means for feeding a plurality of line-wires through the field of operation of said clamping-means; means for guiding the stay from said crimping-means to said clamping-means; means for moving such stay through said guiding-means; and means for actuating said first-named feeding means, said first-named carrying-means, said bending-means, twisting-means, second-named carrying means, crimping means, moving-means, clamping means and second-named feeding-means successively in the order named.
39. In a wire-fence machine, means for winding the free ends of one wire about another and crossed wire, comprising the combination of a rotary member having a slot formed therein parallel with its axis of rotation and provided with means for engaging said first-named wire; means for placing said crossed wire in said slot, and simultaneously carrying the other wire to said engaging means; and means for rotating said rotary member.
40. In a wire-fence machine, the combination of a suitable support; a member in said support and having a slot intersecting and

parallel with its axis, intersecting its periphery, and provided with a projecting roller mounted on one end thereof and adjacent to the inner end of said slot; and means for 5 rotating said member.

41. In a wire-fence machine, the combination of a suitable support; a member in said support and having a slot intersecting and parallel with its axis, intersecting its periphery, and provided with a projecting roller mounted on one end thereof and adjacent to the inner end of said slot; and means for 10 simultaneously rotating said member and reciprocating it in the direction of its axis.

42. In a wire-fence machine, the combination of a suitable support; a member threaded in said support and having a slot intersecting and parallel with its axis, intersecting its periphery, and provided with a projecting roller mounted on one end thereof 15 and adjacent to the inner end of said slot; and means for rotating said member.

Signed by me, this 9th day of February 1912,

WILLIAM C. SMITH.
